UNITED STATES PATENT OFFICE.

FREDERICK A. GILBERT, OF BROOKLINE, AND EMIL O. LUNDIN, OF BEACHMONT, MASSACHUSETTS.

ELECTRIC-ARC LAMP.

SPECIFICATION forming part of Letters Patent No. 603,630, dated May 10, 1898.

Application filed July 1, 1897. Serial No. 643,133. (No model.)

To all whom it may concern:

Be it known that we, FREDERICK A. GILBERT, of Brookline, county of Norfolk, and EMIL O. LUNDIN, of Beachmont, county of 5 Suffolk, State of Massachusetts, have invented an Improvement in Inclosed Arc-Lamps, of which the following description, in connection with the accompanying drawings, is a specification, like letters and figures on the drawings representing like parts.

This invention has for its object the production of an inclosed arc-lamp of improved construction whereby among other features the trimming is greatly facilitated, means being 15 provided for holding the upper carbon in place while removing the inner globe, so that the operator has both hands free.

The feed-controlling clutch and the contact for the upper carbon are of novel and highly 20 effective construction, and the cap or cover for the inner globe is provided with a novel valve, through which the upper carbon can pass without binding when in use.

The armature of the solenoid is mounted on 25 a tubular member surrounding the upper carbon, the upper end of said member having a piston to enter a centrally-supported dash-pot at the top of the lamp, thereby greatly simplifying the construction of the parts, the 30 feed-controlling clutch being mounted on the lower end of the tubular member.

We have provided novel and effective 35 means for automatically cutting the resistance-coil out of circuit when the lamp is started, the coil being in circuit only when the lamp is not burning or when the upper carbon is burned out, and the resistance-coil is so located as to greatly economize space.

It has been found in practice that in the ordinary inclosed series arc-lamp if the carbon 40 burns out the voltage of the arc will run up to ninety or one hundred, burning out the globe and lower-carbon holder; but in our improved lamp the voltage of the arc will not be increased under such circumstances, so that 45 danger of burning out the globe or lower-carbon holder is decreased to a minimum.

By the construction hereinafter described 50 the upper carbon will when burned out be released from the controlling-clutch, so that the ends of the carbons will come together, and

the current will then pass therethrough and through the series coil to the line without damage to the parts of the lamp. Should the upper carbon by any chance stick when the lamp 55 is burning, the safety cut-out will be operated automatically to cut the lamp out of circuit.

The general construction of the lamp and the various novel features embodying our invention will be hereinafter fully described in 60 the specification and particularly pointed out in the claims.

Figure 1 represents in elevation an arc-lamp embodying our invention, the outer globe and the lamp-case being shown in section, the lamp being shown as in use or when burning. Fig. 2 is a partial vertical sectional view of the armature and coils with the controlling-clutch for the upper carbon in elevation, the clutch being in unclutched position. 70 Fig. 3 is an enlarged longitudinal sectional view of the contact member for the upper carbon. Fig. 4 is a transverse sectional view thereof on the line $x-x$, Fig. 3. Fig. 5 is an enlarged top or plan view of the valve or closure for the inner globe. Fig. 6 is a diametral sectional view thereof on the line $x'-x'$, Fig. 5. Fig. 7 is a detail in elevation and on an enlarged scale of the removable globe-holder and support for the lower carbon. Fig. 8 is a 80 transverse sectional view thereof on the line $y-y$, Fig. 7. Fig. 9 is a partially diagrammatic view of the coils and circuits. Fig. 10 is a lower end view of the armature and tube in which the upper carbon travels. Fig. 11 is 85 an enlarged view, in front elevation, of the lower part of the lamp with the spider drawn down. Fig. 12 is a top or plan view of the cross-bar shown in Fig. 11 with its depending hub, and Fig. 13 is a perspective view of the 90 seat for the inner-globe holder.

Referring to Figs. 1 and 2, the lamp-frame comprises an open upper body portion A, preferably made as a metal casting having a cylindrical base A', the sides having openings 95 therein for the free circulation of air to aid in maintaining the adjacent portions of the lamp cool.

The base A' has (see Fig. 2) an upturned hub A^X and a central aperture through which 100 is passed a longitudinally-movable metal tube B for a purpose to be described, the cage-like

body A receiving therein the usual series-wound and shunt coils C and C', respectively, the core upon which the coils are wound resting on the base A' and being positioned by 5 the hub A^x.

A top A², having an inner hub A³, (see Fig. 2,) closes the body portion, said hub being shouldered at 2 to support a spring S, which assists the solenoid in lifting the tubular 10 clutch-actuator B, the lower end of the hub being recessed to permit full movement of the armature C^x.

A washer 3 of insulating material is interposed between the base A' and a ring A⁴, held 15 in place by suitable insulated screws 4, said ring having attached thereto depending members A⁵, preferably tubular, into which fit telescopically rods A⁶, (see Fig. 1,) secured to a spider A⁷.

20 The lower ends of the tubes A⁵ are rigidly attached to a cross-bar a, having a central opening a', Fig. 12, and cut away at a² between the two lateral ears a³ at the front of the bar, two similar ears a³ being extended 25 laterally from the back of the cross-bar, and beneath the latter depends a tubular hub a⁵, concentric with the opening a', said hub being adapted to pass through the threaded part A⁷⁰ of the spider. The spider is held in 30 place by a suitable nut A⁸, Fig. 1, locked onto the projecting lower end of the hub a⁵ in usual manner, and the shade or outer globe G^x is supported normally in the position shown in Fig. 1 by a socket A⁹, held in place by the 35 threaded part A⁷⁰ of the spider.

The seat a⁴ for the inner-globe holder is shown separately in Fig. 13, it being substantially an open ring-like member having ears a⁴⁰, which are so disposed as to register with 40 the ears a³ of the cross-bar, the seat being held in place on the cross-bar by insulated screws 5 6, while washers 7 of insulating material are interposed between the cross-bar and the seat a⁴.

45 The seat a⁴ is provided with diametrically-located clamping-screws 8, which are engaged by oppositely-turned hooks d, (see Figs. 7 and 8,) laterally extended from a casting D, adapted to rest on the seat a⁴, said casting having 50 a central tubular portion d', through which is extended the lower carbon L, a socket d² receiving the lower end of the inner globe G. A clamping-screw d³, extended through the tubular portion d' of the globe-support, holds 55 the lower carbon firmly in position.

It will be seen by viewing Fig. 8 that when the screws 8 are loosened a partial turn of the globe-support D will withdraw the hooks d from engagement with the said retaining-screws, so that the globe-support and globe 60 can be removed bodily from the lamp. When replacing the globe-support, the reverse operation is carried out, and when the hooked ears d are in position the retaining-screws 8 65 are tightened. This serves to center the lower carbon as well as to provide a readily-oper-

able detachable connection for the globe-support.

Referring to Fig. 2, the clutch-actuator is shown as a tube B, extended longitudinally 70 through the open body A of the lamp, said tube contacting with the base A', although passing freely therethrough, the armature C^x being rigidly secured to the tube by a clamp-screw c^x. (See Fig. 10.) The armature is 75 sleeve-like in form, having a conical upper end and shouldered at c', the armature being longitudinally split, as shown in Fig. 10, so that it may be tightly compressed upon the clutch-actuator B by tightening the screw c^x. 80 The shoulder c' serves to limit the downward movement of the armature by coming in contact with the upturned hub A^x of the base.

The operation of the armature and its series-wound coil C is as usual in other lamps, 85 the current acting through the solenoid to raise the armature and with it the clutch-actuator, the shunt-coil depressing the latter.

The lower end of the tube B is extended below the base A' into a longitudinally-slotted 90 depending guide f, secured to the under side of the base A' and having attached to its lower end a tube f' in alignment with the clutch-actuator B. This tube has rigidly secured thereto a contact device for the upper 95 carbon, said device comprising a disk g, (see Fig. 3,) having an annular flange g' on its under face, the disk supporting a cylindrical casing g², having screwed into it a base g³, suitable screws 10 holding the casing and disk g 100 together. As clearly shown in Fig. 3, the base is curved upward from its periphery to a central boss g⁴, surrounding an aperture g⁵, through which the upper carbon L' freely passes, the top of the base thus presenting an 105 annular seat for a series of radially-disposed independently-movable members g^x. Each of said members has a straight outer edge, an upturned lug g⁶ at its upper end, and a convexed inner edge, increased in width at g⁷, the 110 lower corner of each contact member resting on the annular seat formed by the base adjacent the casing g². The shape of the contact members is such that they tend to drop inward by gravity toward the longitudinal 115 axis of their supporting member, the flange g' serving to limit such inward movement when the upper carbon is withdrawn by engaging the lugs g⁶. When the carbon is inserted, the contact members g^x are pushed 120 outward sufficiently to permit its passage between them, the center of gravity of each member causing it to rest lightly yet surely against the carbon to form a good contact therewith, 125 said contact members and their support being of course made of metal. These gravity contact members always insure a constant contact between the upper carbon and the circuit, the current passing to the support and contact members, as will be described, and by 130 their use any sparking or arcing is prevented when the clutch-wheels leave the carbon.

A ring h , secured to the casing g^2 , has extended laterally therefrom a slotted ear h' , through which is extended loosely an arm h^2 , pivotally connected at its lower end with the 5 inner-globe cover or cap h^x , said arm being notched at its inner side at 12 and having a finger h^3 , by which it and the cap h^x may be lifted. When the cap is in place on the globe G, (see full lines, Fig. 1,) the upper notch engages a cross-pin 13 in the ear h' , a pin 14 preventing accidental withdrawal of the arm from the ear.

The downwardly-flanged cap h^x fits over the upper edge of the globe G, while the central portion of the cap is depressed at h^4 , Fig. 6, and provided with an upturned hub h^5 , exteriorly threaded at its upper end at h^6 .

A centrally-apertured disk h^7 has on its under side a flange threaded at h^8 and outwardly bent at h^9 between the disk and the threaded portion, so that when the latter is screwed on past the thread h^6 of the hub the disk will be held onto the cap, while free to move laterally a limited amount. The upper carbon 20 passes freely though closely through the disk h^7 , which acts as a valve to close the upper end of the globe, but should the carbon be slightly out of alinement or the globe slanted the lateral play of the valve prevents the carbon 25 from binding. Now when the trimmer wishes to trim the lamp he lifts the arm h^2 by means of the finger h^3 until the lower notch 30 engages the detent-pin 13, holding the arm in dotted-line position, Fig. 1, and at the same time the cap h^x is inclined and raised, the inclination of the cap from the horizontal causing the upper carbon to be caught and lifted with the cap. The upper carbon will be held 35 up thereby as long as the arm h^2 is retained 40 lifted by the detent, so that the trimmer has both hands free to effect the proper trimming of the lamp. When the trimming is finished, a slight lift on the finger h^3 will release the arm, so that it and the cap will return to normal 45 operative position, at the same time releasing the upper carbon.

In trimming, the globe G is removed while the cap is lifted, after which the cap is lowered as far as it will go and the upper carbon 50 is pushed up through it and then pulled out, so that a new one can be inserted. The cap is then lifted, as before, holding the upper carbon stationary while the globe is replaced.

A long carbon can be readily inserted by 55 putting the lower end down through the slotted hub a^5 , then turning it up vertically to be passed up through the contact and feed-controlling devices, the opening a^2 in the cross-bar and the open seat a^4 permitting the turning up of the carbon.

The feed-controlling clutch for the upper carbon comprises two preferably grooved metal wheels b , loosely journaled in elongated substantially horizontal slots b' , formed in bifurcated carriers b^2 , pivoted below the wheel-journals at b^3 to arms on a ring b^4 , sliding on the tube f' , which is longitudinally slotted at

f^2 to permit the peripheries of the oppositely-mounted wheels to engage the carbon within the tube. The carriers are outwardly bent 70 to form arms which are pivotally connected by links b^5 with lateral projections on a ring b^6 , rigidly secured to the lower end of the tubular actuator B, and brake-shoes b^7 , adapted to bear at times on the peripheries of the 75 wheels, are pivotally mounted in outward extensions b^8 of the carriers. The lateral projections of the ring b^6 extend through the longitudinal slots of the guide f , as shown in Figs. 1 and 2, permitting movement of the 80 ring up and down as the actuator B rises and falls with the armature C^x of the series-wound coil C. Now, owing to the relative position of the wheels, brake-shoes, and fulcra b^3 of the carriers, when the actuator is raised the 85 links b^5 rock the carriers and bring the brake-shoes b^7 to bear against the wheels, forcing them against the carbon and stopping their rotation, so that the carbon is lifted. When the amount of current passing through the 90 shunt-coil C' increases, the armature and clutch-actuator B will descend, and the carbon is lowered, still held by the clutch, until the ring b^4 is stopped by an adjustable collar b^{10} on the tube f' , and further descent of the 95 ring b^6 will throw off the brake-shoes, releasing the carbon. By adjusting the collar b^{10} the separation of the carbons is mechanically effected to vary the length of the arc.

The current enters the lamp by the line-wire l , Figs. 1 and 9, which is electrically connected with the metallic body A, the current passing thence to the tube B and to the carbon by several paths, principally, however, by the contact members g^x , the contact 100 device as a whole being diagrammatically represented in Fig. 9 at C^x .

We have herein shown the lamp as adapted for use with constant direct currents, the windings of the coils being arranged for that 105 purpose; but by altering the windings and necessary connections the lamp may be used for other systems.

The current passes from one carbon to the other, forming the arc when the lamp is burning, and from the lower carbon L by insulated wire l^x to one end of the coil C, through the latter, and back to line at l' . One end of the shunt-coil C' is connected electrically at c^4 with the body A and its other end with the 115 line-wire l' at c^5 , Fig. 9, so that if the arc becomes too long more current will pass through the shunt, weakening the effect of the series coil C on the armature, which with the clutch-actuator B will descend, so that the control- 120 ling-clutch will permit the proper feed of the upper carbon to properly shorten the arc and thereby maintain the proper length thereof.

The actuator B carries a contact c^6 , adapted at times to engage a fixed contact c^7 , mounted 125 on and insulated from the body A, said fixed contact being connected by a wire l^8 with a resistance-coil R' , the latter being in circuit with line-wire l'' by wire l^4 , Fig. 9. When the

current is turned off, the cut-out circuit $l^3 l^4$ is closed and the carbons are in contact; but when the current is turned on to start the lamp the cut-out resistance R' will cause enough current to pass through the series coil C to raise the armature and separate the carbons, such movement of the armature then breaking the cut-out circuit at $c^6 c^7$, throwing out the resistance R' . Sometimes the upper carbon might stick long enough for the cut-out circuit to be closed, cutting out the lamp, and then the carbon might be released, and as soon as the carbons come in contact the circuit will be completed through them and the cut-out circuit opened.

It will be seen that we dispense altogether with a holder proper for the upper carbon, it being controlled entirely as to its feed by the clutch device described.

20 The resistance-coil R' is wound upon the exterior of the body B , insulated therefrom by a sheet m of mica, preferably, the windings being separated by air-spaces, as shown, and another resistance-coil R is similarly 25 mounted on the body A above the cut-out resistance R' . The resistance R is connected at its upper end at l^8 with the wire l^X and at its lower end to the wire l^4 , so that the more resistance is inserted the greater will be the 30 current in the series coil C and the greater the separation of the carbons and length of the arc. By decreasing the resistance the current in the series coil will be reduced and the arc shortened, so that by varying the resistance the length of arc is regulated.

35 The resistance is varied by a sliding contact c^{12} , mounted on a guide c^{13} , insulated from the body A and connected at c^{14} with wire l^X , a set-screw c^{15} , Fig. 1, holding the sliding contact in adjusted position, the contact moving over and contacting with the windings of the resistance-coil R .

40 Should the upper carbon burn out sufficiently to fall out of the controlling-clutch, the end of the carbon will come together, the current then passing directly through the carbon and series coil to line without any 45 tendency to burn out adjacent parts.

The cut-out circuit operates automatically 50 to cut the lamp out of circuit if the upper carbon should stick, for the tube B will gradually descend until the terminals $c^6 c^7$ of the cut-out circuit contact, thus throwing the lamp out of the line-circuit.

55 Upon suitable standards 35 (see Fig. 2) on the lamp-body A is supported a cylinder D^3 , closed at its upper end and receiving therein a piston D^4 , fast on the upper end of the actuator B , said cylinder and piston forming a 60 centrally-located direct-acting dash-pot to regulate the movement of the upper carbon and prevent sudden jumps thereof which might be caused by the operation of the feed-controlling mechanism.

65 The upper part of the lamp is inclosed in a light ornamental sheet-metal protective cas-

ing M , open at top and bottom to permit free circulation of air therethrough to aid in keeping the lamp cool. At its lower end the casing is flared at M' to extend over the top of the outer globe G^X and is provided with air-inlet perforations m^X , outlets m^3 being provided at the upper end of the casing.

70 A cover M^2 incloses the top of the body A and the adjacent parts, protecting them from dust and injury.

The lamp-hanger H may be of usual construction, with leaders H^2 for the line-wires l and l' .

80 Our invention is not restricted to the precise construction and arrangement as herein shown, as the same may be varied without departing from the spirit and scope of our invention.

Having described our invention, what we 85 claim as new, and desire to secure by Letters Patent, is—

1. In an arc-lamp, a feed-controlling clutch including rotatable members to directly engage the carbon, rocking carriers for said 90 members, brakes mounted on the carriers to prevent rotation of and press said members against the carbon, and an actuator to operate the carriers and control the brakes to thereby raise and lower the clutch bodily, substantially as described.

2. In an arc-lamp, a feed-controlling clutch including rotatable members adapted to directly engage the carbon, rocking carriers for said members, brakes mounted on the carriers, and an actuator to throw the operation of the brakes and thereby throw the clutch into and out of operation and also to raise and lower the same bodily, combined with an adjustable stop to effect release of the carbon 105 at a predetermined point, substantially as described.

3. In an arc-lamp, a feed-controlling clutch comprising rotatable contact members, rocking carriers therefor, brakes mounted on said 110 carriers, to press the contact members against the carbon and prevent their rotation, a tubular actuator in which the upper carbon is freely movable, and connections between said actuator and carriers, to operate the latter and thereby regulate the feed of the carbon, substantially as described.

4. In an arc-lamp, the lamp-body, a depending guide having a longitudinally-slotted, tubular extension through which the upper carbon is loosely extended, combined with a controlling-clutch for said carbon, comprising rotatable contact members, rocking carriers therefor, a support for said carriers, adapted to slide on the tubular extension, brakes on the carriers to act upon and press the contact members against the carbon, a clutch-actuator, and connections between it and the carriers, to operate, substantially as described.

5. In an arc-lamp, a globe having a removable cover, through which the carbon passes, and means to lift the cover and retain it lifted

from the globe for trimming, the cover when lifted engaging and holding the upper carbon stationary, substantially as described.

6. In an arc-lamp, a globe having a removable cover through which the carbon is normally adapted to freely pass, a lifting-arm to which said cover is pivotally jointed, and a detent to retain said arm and cover lifted, the cover when lifted inclining to the horizontal and engaging the upper carbon to prevent its downward movement, substantially as described.

7. In an arc-lamp, a globe-cover having a central upturned hub exteriorly threaded at its upper end, a disk having an opening in which the carbon snugly fits, and a down-turned, outwardly-bent flange on said disk, threaded to engage the hub of the cover, the bent portion of the flange permitting lateral movement of the disk after separation of the said threaded portions, substantially as described.

8. In an arc-lamp, a globe-cover having a central upturned hub, a coöperating disk having an opening in which the carbon snugly fits, and means to retain the disk on the cover while permitting free lateral movement about the hub, substantially as described.

9. In an arc-lamp, a globe-cover having a central opening through which the carbon loosely passes, a coöperating disk apertured to snugly receive the carbon, and a detachable connection between the cover and disk, permitting relative lateral movement thereof without separation, substantially as described.

10. In an arc-lamp, a controlling-clutch for and to directly engage the carbon, a longitudinally-movable tubular actuator therefor in which the carbon is freely movable, a cut-out circuit in which said actuator is included, and a circuit-controller one member of which is fixed and the other mounted on the actuator, movement of the actuator to separate the carbons in starting the lamp breaking the cut-out circuit, substantially as described.

11. In an arc-lamp, an open cylindrical body, series-wound and shunt coils inclosed therein, and a resistance-coil wound upon the exterior of said body and insulated therefrom, whereby said resistance-coil is supported independently of the series and shunt coils, substantially as described.

12. In an arc-lamp, a cylindrical body, series-wound and shunt coils inclosed therein, a resistance-coil wound upon the exterior of said body and in shunt with the series coil, and a sliding regulator to adjust the resistance, substantially as described.

13. A contact device for electric-lamp carbons, comprising a supporting member, and a plurality of independent gravity contact members mounted to rock about their lower ends, said lower ends resting on the bottom of the supporting member, the upper portions of said members having enlargements on their inner faces adapted to rest against the surface of the carbon, substantially as described.

14. A contact device for electric-lamp carbons, comprising a tubular support having a centrally-apertured base, a plurality of independently-movable gravity contact members, mounted at their lower ends on said base and radially disposed around the aperture therein, adapted to rock on their lower ends and move their upper portions into contact with the carbon, and a stop to engage the upper ends of said contact members and limit their inward movement, substantially as described.

15. A contact device for electric-lamp carbons, comprising a tubular support having a centrally-apertured base, and a series of radially-disposed gravity contact members mounted on said base and normally moved by gravity toward the longitudinal axis of the support, the lower ends of said members resting on the base adjacent the tubular support, substantially as described.

16. In an arc-lamp, a main body portion, depending arms connected at their lower ends, clamp-screws on said connection, and a lower-carbon holder provided with oppositely-turned, hooked ears to engage and be held in place by said clamp-screws, substantially as described.

17. In an arc-lamp, a detachable lower-carbon holder having a globe-socket and oppositely-turned hooked ears, combined with a support having clamp-screws to be engaged by said ears, to retain the holder in place, substantially as described.

18. In an arc-lamp, the main body portion, depending arms connected at their lower ends by a cross-bar, a hub thereon longitudinally slotted at one side, and a lower-carbon holder detachably mounted on the cross-bar, substantially as described.

In testimony whereof we have signed our names to this specification in the presence of two subscribing witnesses.
